COMBINATION DESK UNIT

Martin Glaberson, Ardsley, N. Y., assignor to Eversharp, Inc., Chicago, Ill., a corporation of Delaware

Application November 21, 1950, Serial No. 13,077

Term of patent 14 years

(Cl. D74—1)

To all whom it may concern:

Be it known that I, Martin Glaberson, a citizen of the United States, residing at Ardsley, in the county of Westchester and State of New York, have invented a new, original, and ornamental Design for a Combination Desk Unit, of which the following is a specification; reference being had to the accompanying drawing, forming a part hereof.

In the drawing:

Fig. 1 is a perspective view of a combination desk unit, showing my new design;

Fig. 2 is a side elevational view thereof;

Fig. 3 is a front elevational view thereof; and

Fig. 4 is a plan view thereof.

The essential features of my design are shown in full lines, the outline of a fountain pen in broken lines in Fig. 1 has been omitted from the remaining figures for convenience of illustration.

I claim:

The ornamental design for a combination desk unit, substantially as shown and described.

MARTIN GLABERSON.
